OLIVER P. COGGESHALL, OF PROVIDENCE, RHODE ISLAND.

DESIGN FOR APPLICATION TO ARTICLES OF JEWELRY.

Specification forming part of Design No. 7,135, dated January 27, 1871; application filed October 24, 1873.
[Term of Patent 7 years.]

To all whom it may concern:

Be it known that I, OLIVER P. COGGESHALL, of the city and county of Providence, in the State of Rhode Island, have invented a Design for Application to Articles of Jewelry, of which the following is a specification:

The nature of my design is fully represented in the accompanying drawing, to which reference is made.

My design is intended to be used in connection with sleeve-buttons, rings, and watch-seals, and other jewelry; and consists in a representation of a billiard-table with the balls and

cue resting thereon, and the bridge placed in usual position underneath, as shown.

What I claim as new is—

The design herein shown for jewelry representing a billiard-table, balls, cue, and bridge, said design being applied to or placed upon various articles of jewelry, substantially as described.

OLIVER P. COGGESHALL.
